HENRY H. GOVE, OF BIDDEFORD, MAINE; CHARLOTTE M. GOVE ADMINISTRATRIX OF SAID HENRY H. GOVE, DECEASED.

FEELER MECHANISM FOR LOOMS.

Application filed June 26, 1920. Serial No. 391,820.

To all whom it may concern:

Be it known that I, HENRY H. GOVE, a citizen of the United States, residing at Biddeford, in the county of York and State of Maine, have invented certain Improvements in Feeler Mechanisms for Looms, of which the following description, in connection with the accompanying drawings, is a specification, like reference characters on the drawings indicating like parts in the several figures.

This invention relates to automatic looms and is concerned particularly with the feeler mechanisms for looms of this type. As is well understood by those skilled in this art, a very common commercial type of automatic loom comprises a feeler that engages the bobbin in the running shuttle at every other pick, and which operates when the filling on the bobbin reaches a point of critical exhaustion to throw into operation a mechanism which ejects the spent bobbin from the shuttle and inserts a full bobbin therein. It is obvious that the adjustment of the feeler must be very accurate in order to make a loom of this type work satisfactorily. That is, if it initiates the action of the bobbin changing mechanism before the filling has become substantially exhausted, then an unnecessary amount of this filling will be wasted since the weft on the ejected bobbin is so short that it is useless for anything except scrap. On the other hand, if the feeler does not initiate the action of the weft replenishing mechanism before the filling is fully exhausted, the weft will run out at an intermediate point in the shed and thus will produce a flaw in the goods. It is practically impossible, however, to keep a loom in the adjustment required to produce this advantageous result for any length of time. This is a recognized defect in these machines and is produced by many causes, among which may be mentioned especially the imperfect position of the bobbin in the running shuttle, vibration in the machine, and similar conditions. Consequently, it is necessary to readjust the feeler mechanism of looms of this type at very frequent intervals in order to reduce so far as possible the quantity of waste thread on the ejected bobbins and still have the machines weave perfect goods.

It is the chief object of the present invention to cure the defects and overcome the

difficulties above described. Stated more specifically, the invention aims to devise a feeler mechanism which can be adjusted very accurately so that it will cause the bobbin changing or weft replenishing mechanism to operate only when the bobbin in the running shuttle has reached a point of critical exhaustion and which, when once adjusted, will remain in its adjusted condition for a long time. In other words, it is an object of the invention to devise a feeler mechanism which will produce more uniform results than those heretofore used.

The invention also is directed to the provision of a feeler mechanism which will be very reliable in operation, economical to manufacture, will require a minimum of attention, and which can be easily adjusted.

The nature of the invention will be readily understood from the following description when read in connection with the accompanying drawings, and the novel features will be particularly pointed out in the appended claims.

Referring now to the drawings,

Figure 1 is an angular view illustrating a mechanism embodying the present invention and showing it applied to a loom;

Fig. 2 is an end view, partly in elevation and partly in vertical cross section, of the construction shown in Fig. 1;

Fig. 3 is a view similar to Fig. 2 but showing only the parts adjacent to the lay;

Fig. 4 is an angular view illustrating in a skeleton form the mechanism shown in Fig. 1;

Fig. 5 is a side elevation showing the feeler itself and the parts adjacent thereto, and illustrating the feeler in contact with the bobbin in the running shuttle; and

Fig. 6 is a vertical cross sectional view of the parts shown in Fig. 5.

The invention is shown in the accompanying drawings as applied to the well known Northrop loom. A very common type of Northrop loom comprises a feeler mechanism that operates at every other beat-up of the lay to engage the weft or filling in the running shuttle and when the filling in the shuttle reaches a point of critical exhaustion, that is, a point where so little filling remains on the bobbin that it is likely to run out in the shed, the feeler mechanism operates a starting mechanism which initiates the action of the automatic weft re-

plenishing means. This starting mechanism comprises a bar 2, Fig. 4, secured fast on the lower end of a pivot stud that is mounted vertically in a housing 3 forming part of a bracket 4 which is secured rigidly to the breast beam. A spring coiled about the pivot stud tends to swing the bar 2 forward toward the lay.

When the feeler mechanism is tripped 10 due to the depletion of the weft or filling on the bobbin in the running shuttle, this mechanism is operated through the motion of the lay to push the forward end of the bar 2 backwardly along an inclined surface 6 formed on a bracket arm 7 which is supported by one arm 8 of a lever that is fulcrumed at 9 on the stationary bracket 4. This movement of the bar 2 along the incline 6 depresses the lever arm 8, thus raising 15 the other arm 10 of this lever, and the latter arm is provided with a finger that projects into a slot 11 formed in a link 12. A hammer 13, which is constantly operated by a cam motion, normally swings back and forth immediately over the end of the link 12, but when this link is raised in the manner just described its end adjacent to the hammer is brought into the path of movement of the hammer, which then forces the 20 link backwardly, thus acting through an arm 14 fast on the rock shaft 15 to turn this shaft slightly. This shaft 15 is the starting shaft for the transferring mechanism, as will readily be appreciated by those skilled 25 in this art, and the series of operations just described initiates the action of the weft replenishing mechanism which then operates automatically, in this particular type of loom, to eject the spent bobbin and replace 30 it by a full bobbin. After this operation has been completed the starting mechanism immediately drops back into its original condition, the bar 2 being returned to its former position by the coiled spring above 35 referred to, and the starting mechanism thereafter continues to remain in its inactive position until it is again brought into action by the feeler mechanism.

All of the mechanism so far described is 40 exactly like that used in the present Northrop loom. The present invention provides a novel mechanism for initiating the action of this starting mechanism. In the construction shown a bracket 16 is secured to the bar 2 by a set screw that projects upwardly through the bottom of the bracket and is provided with an ear to receive the 45 pivot of a bell crank lever 17.

Two screws 18 projecting through the vertical part of the bracket 16 and threaded in the vertical arm of the lever 17 serve to adjust this lever about its pivot. Secured to the horizontal arm of this lever 17 is a plate 19 carrying a stud 20 on which is pivoted 50 a lever or arm 21, and a spring 22 coiled

about this stud acts on the arm 21 to hold it yieldingly against a stop 23, Fig. 3. The connection between the plate 19 and the lever 17 permits the adjustment of the arm 21 horizontally toward and from the lay, as 55 will be evident from an inspection of Fig. 1, this connection comprising two screws 24 projecting through slots formed in the plate 19 and securing the plate to the lever 17. Since this plate is carried by the bracket 50 16 and since this bracket is adjustable along the arm 2, any desired adjustment of the pivoted arm 21 can be obtained. This arm 21 is actuated upon the call for filling replenishment. In other words, this arm normally is stationary but it is the element to which motion is transmitted to actuate the starting mechanism upon the call for filling replenishment.

The feeler is of the caliper type and comprises a plunger having a forked head to engage the bobbin B. Mechanism is provided to move this feeler into engagement with the bobbin when the shuttle S is boxed on the feeler side of the loom, the feeler being reciprocated vertically into and out of the shuttle box.

As shown in the drawings, this feeler comprises a block or head 25 having plates 26-26 secured to the opposite sides thereof and projecting downwardly therefrom, the lower ends of these plates being turned outwardly slightly away from each other. The plates are bolted to the head 25 and preferably are spaced slightly therefrom by shims 25 so that a very accurate adjustment can be obtained of the spacing of these plates from each other. The feeler is supported on the lower end of a plunger 27 provided with a split socket 28 to receive the ball end 29 on a pin 30 that is secured to the feeler head block 25. A screw 31 secures the two parts of the socket 28 together. In order to limit the turning movement of the ball 29 in the socket 28 a pin 32 is secured fast in 100 the ball 29 and projects at opposite sides thereof into holes drilled in the socket 28, these holes being slightly larger in diameter than the pin so that the feeler can move in any direction about the center of the ball 29, but this movement will be very limited 105 due to the construction just described.

The plunger 27 telescopes within a hollow slide or tube 33 and is guided in a bushing 34 secured by a set screw 35 in the lower end 110 of the tube 33. This plunger has a square head 36 which is guided in a square aperture extending longitudinally through the slide 33 and this slide also is guided in a square aperture formed in a bracket 37 which 115 is secured by bolts 38-38, Fig. 1, to another arm 39 that is adjustable vertically on a bracket 40 secured to one side of the lay L. Screws 41 secure the arm 39 in its 120 adjusted relationship to the supporting 130

bracket 40. It will be evident that the horizontal and vertical adjustments provided between the parts 37, 39 and 40 enable an operator to adjust the feeler into any desired position over the shuttle box. A coiled spring 44 encircling the plunger 27 acts on this plunger to hold it normally at the lower limit of its movement, this limit being determined by the engagement of the head 36 with the bushing 34. Another spring 45 bears at one end on the bracket 37 and at its opposite end against a head 46 provided on the upper end of the slide 33, and holds this slide at the upper limit of its movement. This limit is determined by the engagement of a head or enlargement 47 on the lower end of the slide with the lower face of the bracket 37.

For the purpose of depressing the feeler to move it into engagement with the bobbin B when it is boxed on the feeler side of the loom, a roll 49 is mounted on the upper end of the slide 33, and a cam lever 50 fulcrumed at 51 on the bracket 37 rests on this roll. The upper surface of this lever is engaged by a roll 52 which is supported by an arm 53, the adjacent ends of these levers being slotted, as clearly shown in Fig. 1, so that they may be adjusted relatively to each other, and a bolt 55 extends through both slots to secure these parts in their adjusted positions. The member 54 is secured by bolts 56 to a part 57 that is bolted to the machine frame, the bolts 56 passing through a horizontal slot 58 in the part 54 to enable the latter part to be adjusted horizontally.

It will now be seen that when the lay beats forward toward the breast beam the lever 50 will strike the roll 52 back of the cam surface on said lever, and as the lay continues to move forwardly the lever will be forced downwardly due to its engagement with said roll. This movement of the lever will be transmitted through the roll 49, slide 33, and spring 44 to the plunger 27 and the feeler 25, thus forcing the feeler downwardly into engagement with the bobbin. The plates 26-26 of the feeler are set the proper distance apart to straddle the bobbin when the filling thereon has been reduced to the point of critical exhaustion. Consequently, so long as the bobbin contains sufficient filling so that its diameter exceeds the distance between the plates 26-26, the downward movement of the feeler will be arrested by the bobbin and the remaining downward movement of the slide will result simply in compressing the light spring 44. When, however, the filling on the bobbin is nearly exhausted the feeler will slide down over the bobbin, and this abnormal increase in the stroke or movement of the feeler is utilized to effect the actuation of the starting mechanism for the weft replenishing means.

For this purpose one end of the feeler

head 25 is slotted and an actuator 60 is mounted in this slot on a pivot 61. This actuator is provided with a toe 62 that projects downwardly at one side of the pivot 61 and into the space between the plates 26-26 of the feeler. A spring 63, Fig. 6, acts on the upper surface of this toe to hold the actuator normally in a vertical position, as shown in said figure, but when the feeler moves down astride of the bobbin B into the position shown in Fig. 5, the engagement of the toe 62 with the upper surface of the bobbin swings the actuator in a counter-clockwise direction into the position shown in said figure. This actuator is curved, as shown in Figs. 1 and 3, and its face toward the breast beam is grooved, as indicated at 64, so that after the actuator has been moved into this position, and as the lay continues to swing backwardly, it will engage the forward upstanding end of the arm 21, and, due to the motion of the lay, move this arm backwardly thus forcing the bar 2, Fig. 4, back over the incline 6, depressing the lever 8, and raising the end of the link 12 into position to be struck by the hammer 13. In other words, this movement of the part 60 combined with the motion of the lay actuates the starting mechanism for the bobbin changing apparatus.

It will be seen from an inspection of Figs. 5 and 6 that when the actuator is in its normal position, as shown in Fig. 6, it lies entirely at one side of the arm 21 so that there is no contact between these parts except upon the call for filling replenishment. It will also be seen that the pivotal connection of the arm 21 with the plate 19 enables this arm to swing in a horizontal plane as it is moved backwardly to maintain the engagement of its forward end with one of the notches or grooves 64 during the completion of the swinging movement of the lay. A spring 66, Fig. 1, coiled about the pivot of the lever 50, holds this lever lightly on the roll 49 and prevents it from being thrown off the roll on the upward stroke of the feeler.

The operation of the apparatus is as follows: Starting with the shuttle in the box on the magazine side of the loom the lay starts on its backward stroke and when it reaches approximately the top center the pick occurs and the shuttle is shot through the shed into the box on the feeler side of the loom. After the lay passes the top center on its beat-up stroke the stationary roll 52 engages the cam lever 50 and forces it downwardly thus forcing the feeler into engagement with the filling of the bobbin. It will be seen from an inspection of Figs. 1 and 2 that the rise or cam surface in the lever 50 is considerably back of the end of this lever. Consequently, the downward stroke of the feeler is completed consider-

ably before the lay has finished its beat-up stroke. After the roll has passed over this rise in the cam lever 50 it travels along a surface of the lever which is substantially concentric with the axis on which the lay oscillates so that a dwell is produced in the movement of the feeler.

If it is assumed that the bobbin is practically full at this time, the downward movement of the feeler will be stopped by the engagement of the feeler legs 26—26 with the filling, and the slide 33 will be forced down for a considerable distance over the plunger 27 thus compressing the light spring 44.

15 When the lay again beats backward the feeler will be raised by the strong spring 45 and the roll 52 will leave the lever 50 at the point where it came into contact with it on the beat-up stroke. On the next beat-up stroke the feeler is simply forced down into the empty box.

This process is repeated until the diameter of the bobbin is reduced to a value substantially equal to the distance between the legs 26—26 of the feeler, the actuator 60 being held in its upright position by the spring 63 and moving in a path beside the arm 21 but entirely out of contact with said arm. When however, the filling has become depleted to a predetermined point the feeler will be moved down astride of the bobbin thus rocking the actuator 60 on its pivot and producing the bobbin changing operation as above described.

35 It may here be pointed out that an important advantage of effecting the movement of the feeler into engagement with the bobbin through a light spring, such as 44, and producing the reverse movement by a strong spring, as 45, is that just before the point of predetermined depletion of the yarn is reached for which the feeler has been adjusted, there is a tendency for the feeler to wedge on to the bobbin. This tendency is effectually overcome by the spring arrangement above described since the downward stroke of the feeler is effected through the light spring, while its upward movement out of engagement with the bobbin is effected more powerfully through the strong spring 45. The mounting of the feeler on the plunger 27 so that it can have a limited movement relatively to the plunger also is of advantage in securing accuracy of operation, since it allows the feeler to adjust itself to the bobbin and therefore compensates for variations in the position of the bobbin in the shuttle. These variations in the position of the bobbin might without this flexible mounting of the feeler interfere very substantially with the accuracy and uniformity of operation of the feeler, and it might also produce a wedging action of the plunger in its slide. Any danger of these undesirable results being produced by any reasonable va-

riations in the position of the bobbin are effectually overcome by this construction. These features contribute to the reliability of operation of the mechanism and permit a very close adjustment so that the quantity of 70 yarn or filling to be left on the bobbin can be controlled within very narrow limits. A further advantage of the mounting of the feeler so that it is moved lightly into contact with the yarn is that it substantially 75 eliminates any liability of injuring the yarn, which action might be produced if the feeler were moved forcibly into contact with the bobbin. This would be particularly liable to happen when using fine yarns. In this 80 connection it may also be pointed out that the cam surface on the arm 50 is made such that the feeler strikes the yarn with less force than do the feelers in the present commercial machines with which I am familiar. 85

It will be seen from the foregoing description that the feeler mechanism provided by this invention when once adjusted is entirely independent for its operation on minor variations in the stroke of the lay, and that its adjustment is not affected by variations 90 in this stroke or any vibration of the machine.

While I have herein shown and described the best embodiment of the invention of 95 which I am at present aware, it will be understood by those skilled in this art that this embodiment may be modified in minor details of construction and arrangement of the parts without departing from the spirit or scope of this invention.

What is claimed as new is:

1. In a loom having power operated means for automatically effecting a predetermined change therein, a caliper feeler mounted for engagement with the bobbin in the running shuttle, mechanism for moving said feeler downwardly into the top of the shuttle box into engagement with said bobbin and out of engagement therewith again, and an actuator for said means pivotally connected with said feeler and dependent for its movement into operative position upon a substantial increase in the downward movement of said feeler when the filling on said bobbin reaches a point of critical exhaustion.

2. In a loom having power operated means for automatically effecting a predetermined change therein, a caliper feeler controlling the operation of said means, and supporting and operating mechanism for said feeler operative to move it into and out of engagement with the bobbin in the running shuttle, said mechanism being constructed and arranged to enable said feeler to have a limited universal movement whereby it automatically adjusts itself to the bobbin upon engagement therewith.

3. In a loom shuttle having power op-

erated means for effecting a predetermined change therein, the combination of a starting mechanism for mechanically initiating the operation of said means, an actuator for 5 said mechanism, said actuator being normally held in an inoperative position with reference to said mechanism and arranged to be moved into its operative position by contact with the bobbin in the running 10 shuttle, and a caliper feeler normally preventing the contact of said actuator with said bobbin but operative to effect such contact when the filling on said bobbin reaches a point of critical exhaustion.

15 4. In a loom having power operated means for effecting a predetermined change therein, the combination of an actuator for mechanically initiating the operation of 20 said means, a caliper feeler connected with said actuator, said actuator being mounted for movement relatively to said feeler, and being dependent for its operative movement upon the movement of said feeler.

25 5. In a loom having power operated means for effecting a predetermined change therein, the combination of an actuator for mechanically initiating the operation of 30 said means, a caliper feeler on which said actuator is mounted for movement relatively to said feeler, and means for normally holding 35 said actuator in an inoperative position, said actuator being arranged to have its operative movement produced by an abnormal movement of said feeler.

40 6. In a loom having power operated means for automatically effecting a predetermined change therein, mechanism including a caliper feeler for initiating the 45 operation of said means, means for moving said feeler into and out of engagement with the bobbin in the running shuttle, and an actuator for said power operated means pivotally mounted on the feeler and having a part between the legs of said feeler to engage the bobbin.

7. In a loom having power operated means for automatically effecting a predetermined change therein, mechanism in-

cluding a caliper feeler for initiating the 50 operation of said means, means for moving said feeler into and out of engagement with the bobbin in the running shuttle, an actuator for said power operated means pivotally mounted on the feeler and having a part between the legs of said feeler to engage the bobbin, and means normally holding 55 said actuator in an inoperative position but permitting it to be moved into its operative position upon engagement with said bobbin.

60 8. In a loom having power operated means for automatically effecting a predetermined change therein, a caliper feeler mounted for engagement with the bobbin in the running shuttle, a plunger supporting 65 said feeler, a hollow slide in which said plunger is mounted, a light spring acting between said slide and plunger to move the plunger toward the bobbin, a support for said slide mounted on the lay, a strong 70 spring acting on said slide to move it away from said bobbin, and stationary means for utilizing the motion of the lay to force said slide downwardly against the action of said strong spring.

75 9. In a loom having power operated means for automatically effecting a predetermined change therein, a caliper feeler mounted for engagement with the bobbin in the running shuttle, a plunger supporting 80 said feeler, a hollow slide in which said plunger is mounted, a light spring acting between said slide and plunger to move the plunger toward the bobbin, a support for said slide mounted on the lay, a strong 85 spring acting on said slide to move it away from said bobbin, a cam lever carried by said support and acting on the upper end of said slide, and a stationary roll cooperating with said cam lever upon the beat-up 90 of the lay to depress said lever and slide and thereby move the feeler into engagement with the bobbin.

In testimony whereof I have signed my name to this specification.

HENRY H. GOVE.
